FLUID DISPENSING UNIT FOR PRIMING
ENGINES OR THE LIKE

Gilbert R. Grigsby, Los Angeles, Calif., assignor to
Lubrastart International, Pacoima, Calif.

Filed Nov. 27, 1970, Ser. No. 26,197

Term of patent 14 years

Int. Cl. D15—01

U.S. Cl. D77—1

FIG. 1 is a rear top side perspective view of a fluid dispensing unit for priming engines or the like showing my new design;

FIG. 2 is a front elevational view;

FIG. 3 is a top plan view;

FIG. 4 is a bottom plan view; and

FIG. 5 is a side elevational view of the side opposite that shown in FIG. 1.

I claim:

The ornamental design for a fluid dispensing unit for priming engines or the like, substantially as shown.
